UNITED STATES PATENT OFFICE.

MAX SARFERT, OF PHILADELPHIA, PENNSYLVANIA.

DYING-MACHINE.

SPECIFICATION forming part of Letters Patent No. 786,162, dated March 28, 1905.

Application filed August 3, 1900. Serial No. 25,827.

To all whom it may concern:

Be it known that I, MAX SARFERT, a citizen of the United States, residing in the city and county of Philadelphia, State of Pennsylvania, have invented a new and useful Improvement 5 in Dyeing or Saturating Machines, which improvement is fully set forth in the following specification and accompanying drawings.

My invention consists of an improved construction of a dyeing and saturating machine embodying a rotatable tub or trough, which is adapted to coact with rollers mounted upon a shaft and supported so as to be capable of upward movement, if desired, said trough being supported upon suitable antifriction devices and rotated in any convenient manner.

It further consists of novel details of construction, all as will be hereinafter fully set forth, and particularly pointed out in the claims.

Figure 1 represents a plan view of a dyeing and saturating machine embodying my invention. Fig. 2 represents a vertical sectional view of Fig. 1, certain portions thereof being shown in elevation. Fig. 3 represents a detail view showing the manner of supporting the tub or trough at its center, the devices seen in Fig. 3 being omitted from Fig. 2 for clearness of illustration.

Similar numerals of reference indicate corresponding parts in the figures.

Referring to the drawings, 1 designates a dyeing and saturating machine, consisting of the annular tub or trough 2, which is formed by the inner and outer walls 3 and 4, respectively, and the base portion 5, which in practice preferably inclines outwardly, substantially as illustrated in Fig. 2.

6 designates a central plate which is provided with the bearings 7, adapted to rest in the seat or socket 8, whereby the central portion of the machine is supported, the outer portion of the trough having attached thereto the ring 9, which is adapted to travel upon the antifriction-rollers or similar devices 10, which are preferably conical in shape, the under surface of said ring 9 conforming to the contour of said antifriction devices.

11 designates a rack, which is suitably secured to the trough 2 and is adapted to be in

mesh with the pinion 12, to which power may be imparted in any suitable manner, as by the shaft 13 and pulley 14.

15 designates uprights of a frame or housing, said uprights being located oppositely to each other and having slots or bearings 16 therein, in which are mounted the extremities 17 of the shaft 18, the latter having the rollers 19 rotatably mounted thereon, which may be slightly conical and are adapted to freely revolve in the annular trough 2, said rollers being prevented from longitudinal displacement by means of the collars 20, and by the contact with the walls 3 and 4. The ends of the shaft 18 normally rest in the lower ends of the slots 65 or bearings 16, and when in this position the rollers 19 are held above the bottom of the tub or trough, as shown in Fig. 2. This construction allows the goods that are placed in the tub or trough to pass under said rollers, 70 whereas if said rollers rest on the bottom of the trough the goods are piled up against the same and seriously affect its operation. Moreover when the rollers rest upon the bottom of the trough they are apt to injure and 75 macerate the goods, especially when the machine contains only a small quantity.

The operation is as follows: Through the medium of the pinion 12 and rack 11 rotation is imparted to the annular trough 2, the latter 80 being supported during its movement and the friction thereof reduced to a minimum by reason of the antifriction devices 10. The goods to be dyed and saturated are placed in the trough, which has been previously filled 85 with the liquor, and it will be apparent that through the action of the rollers 19, which are capable of revolving independently of or simultaneously with the shaft 18, said goods will be thoroughly and completely saturated. 90 The rollers 19 are prevented from displacement by reason of their contact with the walls of the trough 2, the outer ends 21 of said rollers being curved to correspond with the curved inner periphery of the juxtaposed wall 95 4 of the trough 2.

In case the rollers 19 encounter a large quantity of goods to be saturated the same can rise, due to the fact that the ends of the shaft 18 are capable of vertical movement in their 100

bearings 16 and that normally the lower periphery of the rollers 19 is a short distance above the bottom 5 of the trough 2, as will be understood from Fig. 2.

5 It will be apparent that other means may be employed for imparting rotation to the trough 2 than that shown and that other changes may be made by those skilled in the art which may come within the scope of my 10 invention, and I do not, therefore, desire to be limited in every instance to the exact construction I have herein shown and described.

Having thus described my invention, what I claim as new, and desire to secure by Letters 15 Patent, is—

1. In a dyeing and saturating apparatus, an annular trough, the base thereof inclining downwardly and outwardly, a shaft mounted above said trough and capable of movement 20 relative thereto, rollers loosely mounted on said shaft and having their outer ends curved to correspond with the contour of said trough, said shaft being supported to normally hold the rollers above and separated from the bottom 25 of said trough, a rack attached to the bottom of the latter, a pinion engaging said rack, a ring secured to said trough, rollers or antifriction devices adapted to coact with said ring, a central plate secured to the inner 30 wall of said trough, a pin depending from said plate and a seat or socket for the reception of said pin.

2. In a dyeing and saturating apparatus, an annular trough, a shaft mounted above said 35 trough and capable of movement relative

thereto, rollers loosely mounted on said shaft, and having their outer ends curved to correspond to the contour of said trough, said shaft being supported to normally hold the rollers above and separated from the bottom of said 40 trough, a rack attached to the bottom of the latter, a pinion engaging said rack, a ring secured to said trough, rollers or antifriction devices adapted to coact with said ring, and a central pivot for rotatably supporting said 45 trough.

3. A dyeing or saturating apparatus comprising a trough, a roller, means for positively supporting said roller out of contact with the bottom of said trough and means for 50 giving said trough and said roller relative rotary motion about the axis of said trough.

4. A dyeing or saturating apparatus comprising a rotatable trough, a roller in said trough and means for positively supporting 55 said roller out of contact with the bottom of said trough.

5. A dyeing or saturating apparatus comprising a trough, a roller, means for positively supporting said roller out of contact 60 with the bottom of said trough, means for increasing the distance between said roller and the bottom of said trough and means for giving said trough and roller a relative rotary motion about the axis of said trough.

MAX SARFERT.
